UNITED STATES PATENT OFFICE.

FRANK WILCOMB, OF NORRISTOWN, PENNSYLVANIA, ASSIGNOR, BY MESNE ASSIGNMENTS, TO HEMPHILL MANUFACTURING CO., OF PAWTUCKET, RHODE ISLAND.

CIRCULAR-KNITTING MACHINE.

1,100,805.

Specification of Letters Patent.

Patented June 23, 1914.

Original application filed November 19, 1906, Serial No. 344,075. Divided and this application filed December 30, 1908. Serial No. 469,986.

To all whom it may concern:

Be it known that I, FRANK WILCOMB, citizen of the United States, residing at Norristown, Pennsylvania, have invented 5 certain new and useful Improvements in Circular-Knitting Machines, of which the following is a specification.

My invention relates to circular knitting machines and concerns particularly the combination of a needle cage surrounding the cylinder and a sectional cam ring whereby the needles may be readily removed and replaced.

It concerns also special features of construction of the cam ring and also such an arrangement of the rotary and stationary parts of the machine as will prevent the sticking of the rotary parts due to expansion under the heat generated in running the machine at the high speed necessary.

My invention concerns also other features as will be hereinafter described and particularly pointed out in the claims.

In the accompanying drawings: Figure 1 is a vertical sectional view through the head of a circular knitting machine embodying my invention; Fig. 2 is a detail vertical sectional view of the cam ring; Fig. 3 is a plan view of the parts shown in Fig. 2; and 30 Fig. 4 is a detail vertical sectional view of a part of the needle cylinder and the cage.

In the drawings, 1 indicates the independently operating spring beard needles; 2 the needle cylinder; and 3 the cam ring carrying 35 the needle cams 4, 5.

The sliding sinkers are shown at 6, and the web holders at 7 operated respectively by cams 8 and 9.

The needles 1 are attached to jacks 1*, the 40 inner edges of which slide in the grooves 10 of the cylinder while their outer edges slide in grooves of a cylinder cage 11 hereinafter referred to. The needle jacks are operated vertically by cams carried by the cam ring 45 which is formed of the gear section 12 and the cam ring proper 3 attached to the gear section by the screws 13.

The needle cams comprise, as shown in 50 Fig. 2, the upthrow cam 14 and the draw-down cam 15. The latter is adjustable, being connected to a post 16 having a slotted head, the slot of which is engaged by a flange on the adjusting screw 17. A jam screw 18 presses and holds the post down in

the position to which it is adjusted. The 55 cam ring is formed in sections, one section 19 which carries the draw-down cam being pivoted at 20, so that it may be tilted back in order that the needle and jacks may be inspected at any time by the operator. This 60 tilting cam section is held in its closed position by the set screws 21, supported by the fixed sections and entering the tilting section. One section of the cam ring or cylinder is completely removable in order to permit the 65 needles and jacks to be removed. This section is shown in Fig. 3 at 22, it being held in place by a button 23, which, on being given a quarter turn, will be in line with a slot 24 formed in the base of the said cam 70 ring or cylinder so that the section of the same may be removed. This cam ring holds the needle jacks in place and shields them from the accumulation of lint and dust. It will be noticed that the lines of division 75 between the sections of the cam ring are not radial but tangential to the circle of needles, and jacks, and therefore the segments form a substantially continuous bearing surface without a break sufficiently large for 80 the needle jack to enter and be caught thereby. This ring may be formed in one piece and slotted up afterward, and even though crevices are left these will not receive the needle stems which must move radially in order to remove them. This tangential slotting also allows the tilting cam section to be pivotally mounted with parallel lines at the pivotal point. 85

Another feature of my invention relates 90 to the construction and arrangement of parts enabling me to replace any needle in the machine without the necessity of removing the cylinder from the machine as is done with most hosiery machines and without 95 pulling the needle upwardly as is done in most rib machines. In removing the needles in the machine built according to this invention it is not necessary to disturb any of the working parts and with this result in 100 view I employ the needle cage 11 above mentioned. This cage is made up of tempered metal strips held in a ring 25 at the lower end of the cage and within the same and by a ring 26 at the upper end of the cage and 1 inclosing the same. The cage may be supported by its ring 25, which is connected to the cylinder. The strips are spaced ap-

to conform radially to the grooves in the cylinder. They afford wide guiding walls for the needle jacks to work between. I have arranged the ring 26 so that during 5 the operation of knitting the needle operating jack at the extreme of its upward movement is held accurately between the ring and the cylinder, this being at the time the yarn is being fed to the needle and the said 10 needle jack is held accurately in its path by the encircling sectional cam ring in its lowest position as well as in its highest position. When, now, a needle or needle jack is to be replaced, the section 22 of the cam ring is 15 detached by turning the button or screw and the needle and jack are drawn radially until the needle stem comes in contact with the top encircling cage ring when it may be pulled downwardly and out from the machine, as in Fig. 4. The new needle and 20 jack are introduced by a reversal of these movements. The cam ring for the needles is driven through the gear 27 on the vertical shaft 28. This gear together with the gear 25 29 for operating the web holder cam ring may be adjusted in relation to each other and the sinker operating mechanism to properly time these parts; and the sinker driving gear 29^x may be adjusted also. 30 It will be understood that while I show a machine in which the needle cylinder is stationary the invention may be applied to the opposite type of machine. It will be understood also that all the features above described 35 are embodied in the one machine.

It will be observed that the needle shanks are guided by both the cylinder grooves and the cage grooves, and they are thus held accurately in position and it will be observed further that the needle jacks engage both the cylinder groove and the cage groove and are therefore guided and spaced accurately thereby.

This invention is a division of that disclosed in an application for Letters Patent 45 of the United States filed November 19, 1906, Serial Number 344,075.

I claim as my invention:

1. In a cam ring for knitting machines, the combination of a drawing-down cam, 50 and a tilting section carrying said cam, said section turning on horizontal pivots, substantially as described.
2. In combination in a circular knitting machine, needles, a cylinder, a cylinder cage, 55 a ring at the upper end of the said cage, a cam ring surrounding the lower part of the said cage and needle jacks guided by the said cage and held in place against lateral displacement when in their uppermost position 60 by the ring and when in their lowermost position by the cam ring, substantially as described.

In testimony whereof, I affix my signature in presence of two witnesses.

FRANK WILCOMB.
